UNITED STATES PATENT OFFICE.

JOHN ELLIOT PEIRCE AND HARRY I. SHINKLE, OF DAYTON, OHIO.

DESIGN FOR A DISPLAY-CABINET.

SPECIFICATION forming part of Design No. 23,118, dated March 13, 1894.

Application filed February 8, 1894. Serial No. 499,540. Term of patent 3½ years.

To all whom it may concern:

Be it known that we, JOHN ELLIOT PEIRCE and HARRY I. SHINKLE, citizens of the United States, residing at Dayton, in the county of Montgomery and State of Ohio, have invented and produced a new and original Design for Show-Cases; and we do declare the following to be a full, clear, and exact description of the same, reference being had to the accompanying drawing, forming a part thereof.

Our design relates to cabinets or display cases, and has for its object to furnish a useful and ornamental case for displaying merchandise or other articles.

The principal features of the design consist in an oblong case with the upper portion thereof formed in a series of panels of a uniform curvature, while the lower front portion of said case has a similar number of rectangular panels. An end elevation of the case will present, in outline, an acute angle joined by a curve, while the front elevation will show the upper portion receding in a convex curve, from the horizontal front panel.

In the annexed drawing A represents the

end panels with a strip of molding (a) extending horizontally through the center thereof, and the upper portion of a curvilinear form as at (b).

B denotes a series of curved lids comprising the top of the case, and in which are set a corresponding number of panels C of a similar curvature.

D is a horizontal panel constituting the front of the case, and E represents a series of 35 oblong-hexagonal panels of uniform diameters set therein.

F designates a corresponding number of 40 rectangular panels of less diameter, set in the center of panels E.

We claim—

The design for a display cabinet substantially as herein shown and described.

In testimony whereof we affix our signatures in presence of two witnesses.

JOHN ELLIOT PEIRCE.
HARRY I. SHINKLE.
